United States Patent

Des. 234,958
Patented Apr. 22, 1975

234,958

COMBINED AMPLIFIER AND CASSETTE PLAYER THEREFOR

Takeyoshi Kawano, Kyoto, Japan, assignor to Matsushita
Electric Industrial Co., Ltd., Osaka, Japan

Filed Apr. 17, 1974, Ser. No. 461,768

Claims priority, application Japan Oct. 22, 1973

Term of patent 14 years

Int. Cl. D14—03

U.S. Cl. D26—14 L

FIG. 1

FIG. 2

FIG. 1 is a top, front, and right side perspective view of a combined amplifier and cassette player therefor showing my new design; and

FIG. 2 is a bottom, rear, oblique perspective view thereof, as seen from the opposite side to that of FIG. 1.

Portions of the drawings are shaded to indicate contrast in appearance and portions are diagonally lined to indicate transparency.

I claim:

The ornamental design for a combined amplifier and cassette player therefor, as shown and described.
